UNITED STATES PATENT OFFICE.

HERBERT MORRIS PILKINGTON, OF ARVERNE, NEW YORK, ASSIGNOR, BY MESNE ASSIGNMENTS, TO LITHOTEX CORPORATION, OF NEW YORK, N. Y., A CORPORATION OF NEW YORK.

METHOD OF PRINTING PHOTOGRAPHICALLY.

1,181,163.

Specification of Letters Patent.

Patented May 2, 1916.

Application filed November 1, 1912, Serial No. 729,023. Renewed April 17, 1915. Serial No. 22,194.

To all whom it may concern:

Be it known that I, HERBERT MORRIS PILKINGTON, a citizen of the United States, and a resident of Arverne, Long Island, county of Queens, and State of New York, have invented a certain new and useful Improvement in Methods of Printing Photographically, of which the following is a specification.

10 This invention relates to a method of printing photographically, and more particularly to printing two or more times upon a sensitized surface a design or designs formed on a photographic or other plate through which light rays may be transmitted.

In most photo-lithographic work it is desirable to have the design of which prints are to be made, reproduced a number of 20 times upon the printing surface in order to print off in one operation as many prints or copies as possible. It is desirable in single color or black-and-white printing, to accurately square up and space the different reproductions of the design or designs 25 as closely as possible upon the plate in order to utilize as much of the printing surface as possible, and in multiple color work, it is necessary for good work, that the printing plates each bearing a number of reproductions of different designs or of component parts of the same design, one for each color, should have corresponding reproductions of the designs accurately spaced 30 on them so that in printing from the plates, these corresponding designs will coincide or match up in order that the colors will blend or fit one upon the other to give the desired color effect.

40 My invention consists in a simple, quick and economic method of photographically printing down or reproducing upon a sensitized surface, a design or designs on a photographic or other suitable plate in such manner that the prints from said plates on the sensitized surface will have an accurate predetermined spacing, so that if the design on the plate be a continuous one, the design upon the sensitized surface when developed, will appear continuous and unbroken as on the plate from which it was printed; and if the designs on the plate be spaced apart or separate, the reproductions of the design-bearing plate upon the sensitized surface may have exactly the same

spacing as the several designs on the plate, or a different spacing, as may be desired, it being only necessary for some classes of work with disconnected designs, that the spacing on the final printing plates be accurately predetermined so that the corresponding designs on the different printing plates for multiple color work will exactly match up or register.

It has been proposed to photographically print or reproduce a design a number of times on a sensitized surface from a unit photographic plate bearing such design by means of what is known as a step and repeat machine. By means of such a machine, images of the design on the photographic plate are projected upon the sensitized surface in accurately spaced positions. In the most accurate and rapidly operating step and repeat machines, such as that shown 75 in United States Letters Patent Number 1,131,631, for step and repeat machine, granted on the 9th day of March, 1915, upon an application filed by me, when it is desired to place a very large number of 80 designs on a sensitized surface, if the machine is not rapidly operated, the "wet plates" used may become dry before the completion of the step and repeat operation; and even if the more expensive "dry 85 plates" are used or the machine operated with sufficient rapidity for the use of "wet plates," the initial cost of the step and repeat machine for handling very large plates, and the time required in reproducing the 90 design a great number of times by means of the machine, makes it vastly more economical to utilize my present invention in forming large design plates.

By means of my new method of printing 95 the designs, the number of reproductions of the design may be doubled in a single exposure with the reproductions accurately spaced, and, as hereinafter pointed out, the reproductions of the designs from a relatively small photographic plate—which designs may be placed thereon by means of the step and repeat machine—can be printed directly upon a metal plate having a sensitized surface which may then be developed, rolled up, and etched, as is well understood in the art, so as to be transformed directly into a printing plate; whereas, in the step and repeat machine it would be more desirable and better practice 110

to make the reproductions of the relatively small photographic plate upon a large sensitized glass plate, and then print from this onto the sensitized metal surface.

In carrying out my invention, I take a photographic or other suitably formed plate (usually a negative) bearing a design or designs which are to be reproduced and having suitably spaced register marks formed thereon, and I place in a suitable printing frame, a plate of metal, stone or glass having a sensitized surface upon which the designs are to be printed, and upon this I place the photographic negative plate and expose the same to a suitable source of light while protecting from light rays the part of the sensitized surface not covered by the negative. I then render visible the register marks reproduced on the sensitized surface adjacent the unexposed portion thereof, or if such marks are visible but not sufficiently so to be plainly seen through the negative plate, I render them more plainly visible, and then by means of said visible marks and the marks on the other end of the negative plate, I place the negative plate upon the adjacent unexposed part of the sensitized surface with said register marks on the negative plate registering with the developed register marks on the sensitized surface; and I then make a second exposure while protecting from light rays the previously exposed portion of the sensitized surface and the remaining unexposed portions, if there be any, and so on, each time accurately placing the negative plate upon the sensitized surface by means of the register marks on the plate and the visible register marks on the previously exposed portion of the sensitized surface. In this way as large a printing surface as desired may be very rapidly and economically prepared with the different reproductions of the designs most accurately spaced thereon.

In the present manner of practising the invention, the sensitized surfaces used are of such a character that the portions of the sensitized surface exposed to the light rays will, after exposure, have a faint orange color, so that after an exposure of the sensitized surface through the negative plate, the portions of the designs and the register marks through which the light rays have been transmitted, will be faintly visible but not sufficiently visible to be accurately detected when viewed through the negative plate for the purpose of placing said plate in its next position on the sensitized surface; and in order to render certain of the register marks more plainly visible or, in other words, to develop them, a little lithographic ink is applied to the marks, which are then wiped with a moistened brush or the tips of the operator's fingers, whereupon the ink will be removed from the portion of the sensitized

surface surrounding the marks which was not exposed to the light rays, thus leaving the register marks black and plainly visible. It is probable that with some sensitized surfaces the register marks will not appear visible at all to the naked eye after exposure; but the portions of the sensitized surface which were covered by the marks on the negative plate may be suitably treated, as is well understood in the art, to render said marks visible. If the sensitizing solution used is one containing one or more of the haloid salts, the register marks on the sensitized surface, upon removal of the negative plate after exposure, will appear sufficiently visible for the purpose of matching the register marks of the negative plate thereon without further treatment. It will thus be seen that, with the use of some sensitizing solutions, it may not be necessary to treat the register marks to develop or bring them out; but wherever in the appended claims I have used the word "develop" or "developing," I wish to be understood as meaning the treatment of invisible marks on the sensitized surface to develop them or render them visible, or the treatment of faintly visible register marks to develop them or render them more plainly visible.

I have found in practice that it is preferable, in forming large printing plates, to make, by means of a step and repeat machine a photographic negative plate bearing a certain number of reproductions of the design and with register marks thereon, the number of reproductions thus formed on the negative plate depending upon the size of the designs being reproduced and the final number desired; and to then use the photographic negative thus formed as a photographic design-bearing plate, and print from this relatively small negative plate upon the final sensitized metal or other surface in accordance with my present invention. The final plate may then be developed, rolled up and etched to transform it into a printing surface.

A suitable machine for carrying out my invention as now practised is shown in the accompanying drawings, in which—

Figure 1 shows a printing frame for receiving the sensitized surface and the photographic plate; Fig. 2 is a sectional elevation taken on line 2—2 of Fig. 1 and showing a suitable vacuum pump connected to the frame; Fig. 3 shows a zinc plate in the course of preparation with two impressions from one negative, and with the negative in position thereon; and Fig. 4 shows a zinc plate having two impressions thereon from a photographic plate bearing a continuous design.

The printing apparatus consists of a suitable box 1, the bottom 2 of which forms

a support in which the sensitized printing plate 3, preferably of zinc, and the photographic plate or negative 4 rest. The box is provided with a pad of rubber 5 having a rubber beading 6 around its edges, and a suitable framing piece 7 and a sheet of glass 8 fit within the box so as to hold the sensitized surface and the negative in place. The frame is supported in any convenient manner and preferably on trunnions 9 so that the frame may be swung in different positions.

The negative plate 4 has a number of reproductions of a unit design 10 thereon, and suitable register marks 11-11' which are preferably formed photographically on the plate in the stepping and repeating of the unit designs thereon. This negative plate, say of half the size of the desired printing surface, is placed in the printing apparatus 1 on top of the sensitized surface of the zinc plate which rests upon the rubber blanket. The portion of the sensitized surface not covered by the negative plate is then covered by a suitable opaque mask 12, and the framing piece 7 with the glass plate 8 is then placed in position in the frame so that its edges rest on the beading 6 of the rubber pad; and it is fastened in position by suitable catches 13. A suitable tube 14 connects the space between the rubber blanket and the glass plate 8 with a vacuum pump 15 by means of which air is exhausted from between the rubber pad and the glass plate, thereby causing the rubber pad, the zinc plate, the negative and the glass plate to be firmly pressed together, and the negative and zinc plate to be held securely in position. A print is then made in the usual way 40 exposing the frame to the light. When the sensitized surface has been sufficiently exposed, the light is shut off from the printing frame, and the frame is opened and the negative and the mask removed. The two 45 register marks 16' now printed upon the sensitized surface from the register marks 11' of the negative plate, may, with the rest of the design, appear in a faint orange tone, whereupon the operator moistens his finger 50 or a brush with lithographic ink and daubs it on the marks, and then moistens his finger with water and daubs the mark again, whereupon the ink is removed from the unexposed part of the plate and the mark is rendered 55 black so that it will be plainly visible through the negative plate. The negative plate is then placed over the unexposed portion of the sensitized surface with its register marks 11 registering with the developed 60 register marks 16' on the sensitized surface, and the mask is transferred to the former position of the negative plate, whereupon the parts are again clamped in position and a second exposure made.

65 It will be understood that it is immaterial

to my invention whether a mask be used to protect the part of the sensitized surface not covered by the negative plate, or the source of light be so arranged and projected as to be confined to the negative plate, or the uncovered portion of the sensitized surface protected in any other suitable manner now known.

It will be observed that in Fig. 3, the spacing between the two reproductions or prints from the negative plate is greater than the spacing between the several designs of the negative plate, while in Fig. 4, it will be observed that the design is continuous without any break therein; and from these drawings it will be apparent that the spacing between the two reproductions of the negative plate may be made equal to the spacings between the several designs of the plate, or made different therefrom as desired. But in all cases, the two or more reproductions will have an exact predetermined spacing, so that in different plates thus made for multiple color work, the corresponding reproduced units will register one with the other.

While I have described my invention using a negative photographic plate with the designs formed thereon photographically, it will be obvious that my invention may be practised with any plates having one or more designs placed thereon by any suitable method as, for instance, by transfer work, painting, etching, stenciling, etc., and with register marks photographically or otherwise formed thereon so long as the register marks will be reproduced on the sensitized surface with the design from the plate.

Having thus described my invention, what I claim as new and desire to secure by Letters Patent, is:

1. The method of photographically printing from a design-bearing plate two or more times upon a sensitized surface the design or designs on said plate, which comprises placing, in front of a portion of a sensitized surface a design-bearing plate through which light rays may be transmitted and having register marks on different portions thereof, making a photographic print of said design or designs and register marks from said plate onto the sensitized surface, placing the plate in front of an adjacent portion of the sensitized surface and adjusting the plate and sensitized surface relatively by the registration of certain of the register marks on the plate with certain of the marks printed on the sensitized surface from the plate, and then making another print from the plate onto said sensitized surface.

2. The method of photographically printing two or more times upon a sensitized surface from a design-bearing plate the design or designs on said plate, which com-

comprises placing, in front of a portion of a sensitized surface a transparent design-bearing plate having register marks near opposite ends thereof, making a photographic print of said design or designs and register marks from said plate onto the sensitized surface, while protecting from light rays the portion of the sensitized surface not covered by the plate, developing certain of the register marks thus printed on the sensitized surface from the register marks near one end of the transparent plate, placing the plate in front of an adjacent portion of the sensitized surface and adjusting the plate and sensitized surface relatively by the registration of certain of the register marks of the plate with the developed register marks on the sensitized surface, and then making a second print from the negative plate onto the sensitized surface while protecting from light rays the portion of the sensitized surface not covered by the plate.

3. The method of photographically printing successively upon different portions of a sensitized surface a design or designs of a photographic plate having register marks at opposite ends thereof, which comprises placing the photographic plate upon a portion of the sensitized surface and making a photographic print of the design or designs and the register marks from said plate onto the sensitized surface while protecting from exposure the portion of the sensitized surface not being thus printed upon, shifting the photographic plate to an adjacent unexposed portion of the sensitized surface and adjusting the plate in position thereon with respect to the previously made print, by matching upon the register marks thus printed on the sensitized surface at the end of the design adjacent the unexposed surface the register marks on the photographic plate opposite the end from which the matching marks on the sensitized surface were printed, and then making a second photographic print of the design or designs upon this unexposed portion of the sensitized surface while protecting from further exposure the portion of the sensitized surface previously exposed.

4. The method of printing designs two or more times upon a sensitized surface to be developed into a direct printing surface, which comprises placing upon a portion of a sensitized surface a negative photographic plate with one or more reproductions of the design and with register marks photographically formed thereon, making a photographic print of said design or designs and register marks from said plate onto the sensitized surface of the plate to be developed into a direct printing surface while

protecting from light rays the portion of the sensitized surface not covered by the negative plate, developing certain of the register marks thus printed on the sensitized surface from certain of the register marks of the negative plate, placing the negative plate on an adjacent portion of the sensitized surface and adjusting the plate and sensitized surface relatively by the registration of certain of the register marks of the plate with the developed register marks on the sensitized surface, and then making a second print from the negative plate onto the sensitized surface while protecting from light rays the portion of the sensitized surface not covered by the plate.

5. The method of photographically printing successively upon different portions of a sensitized surface a design or designs of a photographic plate having register marks at opposite ends thereof, which comprises placing the photographic plate upon and in direct contact with a portion of the sensitized surface, producing a vacuum between the sensitized surface and the photographic plate to bring them into direct contact and hold them from relative movement, exposing to light rays the portion of the sensitized surface thus covered by the photographic plate to make a photographic print of said design or designs and register marks from said plate onto the sensitized surface while protecting from exposure the portions of the sensitized surface not covered by the plate, developing the register marks thus printed on the sensitized surface adjacent an unexposed portion thereof to be next printed upon, placing the photographic plate upon the adjacent unexposed portion of the sensitized surface and adjusting it in position thereon with respect to the previous print thus made, by matching upon the register marks thus developed the register marks at the end of the plate opposite the ones from which the developed marks were printed, and again producing a vacuum between the sensitized surface and the photographic plate to hold them into direct contact and from relative movement, and photographically printing the design or designs from the plate onto the portion of the sensitized surface covered by the plate while protecting from exposure the other portions of the sensitized surface which have been previously exposed or are to be exposed.

In testimony whereof, I have signed my name to this specification, in the presence of two subscribing witnesses.

HERBERT MORRIS PILKINGTON.
